UNITED STATES PATENT OFFICE.

ERNEST FRANKLIN HODGSON, OF NEEDHAM, MASSACHUSETTS.

ROOF CONSTRUCTION.

1,028,725.

Specification of Letters Patent.

Patented June 4, 1912.

Application filed January 11, 1911. Serial No. 601,947.

To all whom it may concern:

Be it known that I, ERNEST F. HODGSON, a citizen of the United States, and a resident of Needham, in the county of Norfolk and 5 State of Massachusetts, have invented a new and Improved Roof Construction, of which the following is a full, clear, and exact description.

The invention relates to portable houses, 10 and its object is to provide a new and improved roof construction whereby a free circulation of air is had with a view to keep the interior material dry, to prevent decay and interior sweating during cold weather, 15 and to keep the roof cool during hot weather.

A further object is to arrange the waterproofing material in such a manner that it is protected against the sun, snow, rain and 20 ice as well as during transportation, thus prolonging the life of the roof. For the purpose mentioned an air space is formed between the outer and inner sheathings, the air space having connection with the atmosphere at both the upper and lower ends, 25 and the sheet of waterproof material is interposed between the sheathings.

A practical embodiment of the invention is represented in the accompanying drawings forming a part of this specification, in 30 which similar characters of reference indicate corresponding parts in all the views.

Figure 1 is a transverse section of the roof construction; Fig. 2 is a longitudinal section of the same on the line 2—2 of Fig. 1; and Fig. 3 is an enlarged cross section of a modified form of the roof construction showing the air outlet by way of the ends 35 of the ridge cap.

Single-boarded roofs, as generally used in the portable construction, are hot in summer and frost or sweat in the interior in cold weather. The air space overcomes these 40 objections especially if the air can circulate or pass through the space.

Roofs are made waterproof in two ways, the most popular being a waterproof material over the outside of the roof boarding, as is the common custom in nearly every 45 roof construction, canvas, metal, or any ready roofing being used. For a portable construction there are three serious objections to this method: First, it is exposed and likely to be damaged during transportation; 50 second, it is exposed to the extreme weather;

elements and its life is very short; and, third, all these materials have a "shedy" appearance which is undesirable. The second way that is quite extensively used is, a roof with its outside or exposed covering 60 of siding, clapboards or especially milled boards, under which and against the same is a waterproof fiber consisting of most any of the ready roofings. Any moisture that passes through the outside covering is carried away by the waterproof fiber. This construction makes a better appearing roof, but on account of the outer boarding coming in contact with the waterproofing directly under it dampness and sweating and 65 a rapid deterioration of the materials is caused. With my improvements presently to be described in detail, the above defects are overcome.

The outer and inner sheathings A and B 70 of the roof are spaced apart to form an air space C, which opens at its lower end into the atmosphere, outside of the side wall D of the house and adjacent to the face board E of the eaves, as will be readily understood by reference to Fig. 1. The upper end of the inner sheathing B terminates on the corresponding side of the ridge pole F, preferably made of two beams fastened together by bolts G or other suitable means, and the upper end of the outer sheathing A terminates a short distance from the corresponding side of the ridge pole F to form 75 a passage C' leading from the upper end of the air space C to an outlet air space C² produced by the use of a metallic ridge cap H passing over the ridge pole F and extending at both sides above the upper portion 80 of the outer sheathing A. The lower edge portion H' of the ridge cap H is corrugated and rests on a longitudinally-extending filling in strip I attached to the outer face of the outer sheathing A. Thus by the arrangement described air can pass 85 into the lower end of the air space C and travel up the same between the inner and outer sheathings A and B, and then air passes through the passage C' into the outlet air space C², from which air passes under the corrugations H' into the atmosphere. Thus the air is caused to circulate through 90 the air space with a view to keep the interior materials of the roof dry with a view to prevent decay and interior sweating during cold weather. The air 95

110

space arranged in the manner described keeps the roof cool during hot weather. It is understood that the inner and outer sheathings A and B are connected 5 with each other at intervals by battens J, and the said sheathings are supported on rafters K made in sections fastened together by bolts K' or other suitable means. A sheet L of waterproof material is placed 10 on the top surface of the inner sheathing B and also extends up the corresponding side of the ridge pole F and the rafters K, so that the sheet L of waterproof material is completely protected against the influence 15 of the heat from the sun, against rain, snow, and ice, and also against injury while transporting the portable house from one place to another.

As illustrated in Fig. 3, the air from the 20 passage C' passes up into the hollow roll H² of the ridge cap H³ to finally pass out of said roll at the ends thereof into the atmosphere. It will be understood that the sides of the roll H² are spaced from the 25 sides of the ridge pole F', so as to allow the air passing up the air space C to travel through the passage C' into the roll H². In this case the side extensions H⁴ of the ridge cap H³ are not corrugated and the 30 sides are fastened on the battens I' arranged longitudinally and secured to the outer sheathing A. The sheet L' arranged on the top surface of the inner sheathing B is extended up the sides and the top of the 35 ridge pole F', as indicated in Fig. 3, so that the sheet L' is protected against the weather and while transporting the roof in sections from one place to another.

Having thus described my invention, I 40 claim as new and desire to secure by Letters Patent:

1. A roof construction, comprising a ridge pole, spaced outer and inner sheathings forming between them an air space, 45 the eaves end of which opens into the atmosphere, the outer sheathing terminating short of the ridge pole forming at the side of the ridge pole an air space communicating with the first air space, a longitudinal strip on the outer sheathing adjacent to the upper end thereof, and a ridge cap 50 extending over the ridge pole and having a side extension projecting over the outer sheathing and secured to said strip, said 55 cap forming an air space opening into the

atmosphere and into which the space at the side of the ridge pole opens.

2. A roof construction, comprising a ridge pole, spaced outer and inner sheathings forming an air space between them, 60 the outer sheathing terminating short of the ridge pole, the eaves end of the said air space opening into the atmosphere, and a ridge cap over the ridge pole and extended over the outer sheathing, the lower edge 65 of the said extended portion of the ridge cap being corrugated and forming with the outer sheathing a second air space communicating with the upper end of the said first-named air space and leading to the 70 atmosphere.

3. A roof construction, comprising spaced outer and inner sheathings forming an air space between them, the eaves end of the air space opening into the atmosphere, a 75 ridge pole extended above the outer sheathing and spaced a short distance from the upper end of the same, a ridge cap over the ridge pole and extended over the upper portion of the outer sheathing, the lower edge 80 of the said extended portion of the ridge cap being corrugated, and a longitudinally-extending filling in strip held on the outer sheathing and on which rests the said corrugated portion, the said extended portion 85 of the ridge cap forming with the outer sheathing an air outlet communicating with the upper end of the said air space.

4. A roof construction, comprising a 90 ridge pole, spaced inner and outer sheathings, the outer sheathings terminating short of the ridge pole, the said sheathings forming an air space communicating with the atmosphere at the eaves, sheets of waterproof material extending over the outer 95 surface of the inner sheathings and on the sides of the ridge pole, filling strips on the outer sheathings adjacent to the upper ends, and a cap on the ridge pole and extending over the outer sheathings onto the filling 100 strips, the lower edges of the cap being corrugated.

In testimony whereof I have signed my name to this specification in the presence of two subscribing witnesses.

ERNEST FRANKLIN HODGSON.
